(57) CLAIM

The ornamental design for a charger for a communication device, as shown and described.

DESCRIPTION

FIG. 1 is an isometric view of an ornamental design of a charger for a communication device showing our new design;

FIG. 2 is a top orthographic view thereof;

FIG. 3 is a right side orthographic view thereof;

FIG. 4 is a left side orthographic view thereof;

FIG. 5 is a rear orthographic view thereof; and,

FIG. 6 is a front orthographic view thereof.

The broken lines shown in FIGS. 1–6 are included for the purpose of illustrating environmental elements only and form no part of the claimed design. The bottom view is omitted and forms no part of the claimed design.

1 Claim, 4 Drawing Sheets
